PNEUMATIC CONCRETE PLACING MACHINE

Filed Aug. 1, 1925

Inventor

James E. Bushnell

By his Attorney

S. J. Cos.

UNITED STATES PATENT OFFICE.

JAMES E. BUSHNELL, OF NORTH PLAINFIELD, NEW JERSEY, ASSIGNOR TO RANSOME CONCRETE MACHINERY COMPANY, OF PLAINFIELD, NEW JERSEY, A CORPORATION OF NEW JERSEY.

PNEUMATIC CONCRETE-PLACING MACHINE.

Application filed August 1, 1925. Serial No. 47,476.

The improvements relate generally to apparatus for conveying and placing concrete and the like by compressed air, and more particularly to the closure of the vessel in which the plastic concrete or concrete forming aggregates are deposited and from which they are expelled by compressed air in the conveying and placing operation. They are in the nature of an improvement in certain parts of the apparatus described and claimed in the copending application of James H. Fitzgerald, Serial Number 754,717, filed December 9, 1924, Patent No. 1,658,046, and are designed primarily to provide in such an apparatus pneumatic means for closing the receptacle after the charge has been placed therein, and also to provide an improved closure and accessories.

The improvements are illustrated in the accompanying drawings, in which

Figure 1 is a longitudinal section, partly in elevation of an apparatus embodying the improvement; and

Figure 2 is an elevation illustrating a method of connecting the air valve handles.

The vessel 1 is closed except for the charging inlet 2 and the outlet 3, and is provided with a worm 4 for propelling the materials toward the outlet, a compressed air inlet 5 and a housing 6 in which may be located a motor or other means for rotating the worm, all mounted on a suitable base 7, as in said copending application. The top compressed air inlet 5 may be used when desired, and may be employed to clean the vessel. Air pressure, however, sufficient to expel the contents, will be established by air entering it from the compressed air pipe 8, which also propels the materials through the discharge conduit 9 to the point of placement.

The inlet or charging opening 2 has a reinforcing ring 10 on which is mounted a hopper 11, and in which is set a sealing gasket 12. In an extension 13 of this ring is a pivot 14 on which a curved door carrying arm 15 and an operating arm 16 therefor are mounted. The curvature of the arm is such that when it swings downwardly to open the door it will also swing toward the head of the drum and carry the door away from the charging opening. It is mounted on a collar 17, to which the operating arm 16 is

also keyed, and this collar is located in and fills an opening 19 in the hopper. As the door 20 is loosely hung, by means of the pivot 21, on the end of the arm 15, it will swing when the charge strikes it on entering the vessel and will not obstruct the flow of materials thereinto. The pivotal connection also permits the door to seat accurately against the gasket 12 and form an air tight seal.

A cylinder 22 for compressed air is mounted on the base 7 by means of a bottom bracket 23 pivoted at 24 to a support 25 on the said base. This connection permits the cylinder to have a slight rocking movement to accommodate it to the arc described by the arm 16. The cylinder is provided with a suitable piston or plunger connected with the arm 16 by means of a suitable piston rod 26 for operating the door. A flexible compressed air pipe 27 communicating with the top of the cylinder is supplied with compressed air through the pipe 28 leading to the main compressed air line 29.

A valve 30 operated by a valve handle 31 controls the supply of compressed air to the door operating cylinder, but on the pipe 8, between the valve 32, controlling the supply of compressed air to the vessel and discharge conduit, and its outlet, is a by-pass 33 communicating between the said pipe 8 and the compressed air pipe 28 for the cylinder, so that when the main valve is opened to admit compressed air to the vessel and discharge conduit, pressure will be instantly established in the door operating cylinder and the door closed, if it has not been closed by the opening of the valve 30. This insures the closing of the door as soon as the compressed air is turned on to the vessel, and also enables the operator to operate the door, and simultaneously turn on or off the compressed air supply to the vessel by means of a single valve. A check valve 34 on the pipe 33 prevents air from passing from the pipe 28 to the pipe 8 so that when the door operating air is turned on ahead of the air for the vessel it will not escape therethrough. The preferred practice is to close the door before air is turned on to the vessel, so that the air will not escape through the door and will not blow the finer aggregates therethrough, and this may be accomplished by simply opening the valve

30 a little in advance of the valve 32. Automatic means for accomplishing this are illustrated in Figure 2 in which the valve handle 31 and the valve handle 35 of the 5 main valve are connected by a link 36, so that when the former is moved to open its valve the latter will be moved also to open the valve 32. By so adjusting the valves 10 that the former opens quicker than the latter, the desired end can be accomplished. It can also be accomplished by means of the slot 37 and pin 38 by which the link is connected with the valve handle 35, as the 15 said link must first move until the pin is in the forward end of the slot before the handle 35 is moved. This slot also has an opening 39 so that the link can be disconnected from the handle 35, and the two 20 handles operated separately if desired. It will also be seen that by adjusting the valves with respect to their handles both valves may be opened simultaneously. This can also be accomplished by placing another pin in the forward end of the slot 37.

25 What I claim is:

1. A vessel for receiving materials to be discharged therefrom pneumatically having a charging and discharging opening, a conduit for compressed air communicating therewith, a door for closing said charging opening, a door operating arm connected adjacent to said opening to have movement to and from and through the same, a valve in said conduit, a branch conduit leading 30 therefrom between said valve and said vessel, a valve in said branch conduit and a door operating piston in communication with said branch conduit, a second branch conduit leading from the first-named conduit on the opposite side of said valve and 35 communicating with said first branch.

2. A vessel for receiving materials to be discharged therefrom pneumatically having a charging and a discharging opening, a 45 conduit for compressed air communicating therewith, a door for closing said charging opening, an arm connected adjacent to said opening to have movement to and from and through the same, a valve in said conduit, 50 a branch conduit leading therefrom between said valve and said vessel, and a door operating piston in communication with said branch conduit, a second branch conduit leading from the first-named conduit on the 55 opposite side of said valve and communicating with said first branch.

3. A vessel for receiving materials to be discharged therefrom pneumatically having a charging and a discharging opening, a 60 conduit for compressed air communicating therewith, a door for closing said charging opening, an arm connected adjacent to said opening to have movement to and from and through the same, a valve in said conduit, a 65 branch conduit leading therefrom between

said valve and said vessel, and a door operating piston in communication with said branch conduit, a second branch conduit leading from the first-named conduit on the opposite side of said valve and communicating with said first branch and a valve in 70 said second branch.

4. A vessel for receiving material to be discharged therefrom pneumatically having a charging and a discharging opening, a 75 conduit for compressed air communicating therewith, a door for closing said charging opening, an arm mounted adjacent to said opening to have movement to and from the same, said door being mounted on said arm, 80 an air operated device for closing said door, a connection between the same and the door operating arm, and a conduit for air under pressure communicating between the conduit for supplying air to the vessel and said air operated device, a valve for controlling the supply of air to the vessel, and a conduit 85 communicating with the air supply conduit to the door operating device and with the conduit for supplying air to the vessel between the said valve and the vessel. 90

5. A vessel for receiving material to be discharged therefrom pneumatically having a charging and a discharging opening, a conduit for compressed air communicating 95 therewith, a door for closing said charging opening, an arm mounted adjacent to said opening to have movement to and from the same, said door being mounted on said arm, an air operated device for closing said door, 100 a connection between the same and the door operating arm, and a conduit for air under pressure communicating between the conduit for supplying air to the vessel and said air operated device, a valve for controlling the supply of air to the vessel, and a conduit 105 communicating with the air supply conduit to the door operating device and with the conduit for supplying air to the vessel between the said valve and the vessel, and a check device on said last-named conduit preventing the passage of air from the said conduit for supplying air for the door operating device to the vessel. 110

6. A vessel for receiving materials to be 115 discharged therefrom pneumatically having a charging and a discharging opening, a conduit for compressed air communicating therewith, a door for closing said charging opening, an arm mounted adjacent to said opening to have movement to and from the same, said door being mounted on said arm, an air operated device for closing said door, 120 a connection between the same and the door operating arm, and a conduit for air under pressure communicating between the conduit for supplying air to the vessel and said air operated device, a valve for controlling the supply of air for the vessel and a valve 125 for controlling the supply of air to the air 130

- operated device, valve operating handles on the said valves, and a connection between said handles whereby movement of one handle will operate both valves.
5. 7. In the combination of devices specified in claim 6, the said connection being constructed and arranged to operate the said valves in succession, said connection being detachable.
8. In the combination of devices specified

Witness my hand this 29th day of July, 1925, at the borough of Dunellen, county of Middlesex, State of New Jersey.

JAMES E. BUSHNELL.
